(57) **CLAIM**

The ornamental design for storage shelf for disc and cartridge cases, as shown and described.

DESCRIPTION

FIG. 1 is a front perspective view of the storage shelf showing our invention, with the shelf shown broken to indicate indeterminate length, it being understood that the design continues uniformly along its length;

FIG. 2 is a reduced front perspective view of the storage shelf showing our invention, with the shelf shown with further breaks to indicate a longer indeterminate length;

FIG. 3 is an enlarged top plan view of FIG. 1;

FIG. 4 is an enlarged side view of FIG. 1;

FIG. 5 is an enlarged front view of FIG. 1; and

FIG. 6 is an enlarged rear view of FIG. 1; and,

FIG. 7 is an enlarged bottom view of FIG. 1.

The broken line showing of cartridges in FIG. 2 is for illustrative purposes only and forms no part of the claimed design.
